[57] CLAIM

The ornamental design for the fire starter, as shown and described.

DESCRIPTION

FIG. 1 is an isometric view of a fire starter, showing our new design;

FIG. 2 is a right end elevational view thereof;

FIG. 3 is a left end elevational view thereof;

FIG. 4 is a top plan view, the bottom view being a mirror image thereof;

FIG. 5 is a side elevational view thereof;

FIG. 6 is an isometric view of a second embodiment of a fire starter;

FIG. 7 is a right end elevational view thereof;

FIG. 8 is a left end elevational view thereof;

FIG. 9 is a top plan view, the bottom view being a mirror image thereof;

FIG. 10 is a side elevational view thereof;

FIG. 11 is a top plan view of a third embodiment of a fire starter, the bottom view being a mirror image thereof;

FIG. 12 is a side elevational view thereof;

FIG. 13 is a right end elevational view thereof;

FIG. 14 is a top plan view of a fourth embodiment of a fire starter, the bottom view being a mirror image thereof.
